UNITED STATES PATENT OFFICE

BERNIS M. SHIPLEY, OF DAYTON, OHIO, ASSIGNEE, BY WRITTEN ASSIGNMENTS, TO THE NATIONAL CASH REGISTER COMPANY, OF DAYTON, OHIO, A CORPORATION OF MARYLAND

CASH REGISTER

Application filed April 23, 1924. Serial No. 702,433.

This invention relates generally to cash registers, and more particularly to the mechanism thereof which prints the consecutive number. It is shown applied to a machine of the type shown and described in Letters Patent of the United States granted to applicant Bernis M. Shipley, No. 1,610,796 on March 1, 1927, and reference may be made thereto for a complete description of this machine. It is not intended, however, to limit the invention to the form or the embodiment in which it is shown herein, as it has many other adaptations.

The principal object of this invention is to provide a control mechanism which is capable of disabling the consecutive number actuating mechanism, either for a single operation or for a plurality of operations.

With this and incidental objects in view, the invention includes certain novel features of construction and combinations of parts, the essential elements of which are set forth in appended claims and a preferred embodiment of which is hereinafter described with reference to the drawings which accompany and form part of this specification.

Of said drawings:

Fig. 1 is a detail front elevation of the consecutive number driving mechanism and the manual means for disabling this mechanism.

Fig. 2 is a detail view of the two type lines, and one of the gears which drives the type wheels on both lines.

Fig. 3 is a detail view of the total lever plate and the means whereby this plate disables the consecutive number drive.

Fig. 4 is a front elevation of a modified form of the mechanism for disabling the consecutive number drive.

Fig. 5 is a side view of part of the mechanism shown in Fig. 1.

General description

Most machines of the type shown and described in the above mentioned patent are capable of printing items and totals and a consecutive number on a plurality of printing mediums. In the machine of the patent above referred to, the consecutive number printing wheels are given one step or move-

ment on every adding operation of the machine, thereby setting up the next consecutive number thereon. Means are provided in said machine for disabling the consecutive number actuating mechanism during total printing operations. The invention herein disclosed provides means for operating this disabling mechanism during any desired adding operation. Said mechanism is controlled by a depressible key which has two positions of adjustment. Said key is moved into its first position of adjustment by being pushed straight down, and into its second position of adjustment by being rotated when constructed as in Fig. 1, or by being tilted when constructed as shown in Fig. 4, after it has been depressed. Said key will actuate the disabling mechanism as it is depressed. And the key is latched in either of its adjusted positions, in one of which it will be automatically released at the end of the next succeeding operation, while in the other adjusted position it will remain latched until manually released.

Consecutive number type wheels

As shown in the patent above referred to, there are two rods 30 and 31 upon each of which are freely mounted a plurality of consecutive number type wheels 32 and 33, respectively. These type wheels have notches formed therein with which a single set of driving gears 34 is adapted to mesh. Each of the gears 34 cooperates with a type wheel 32 on the upper rod 30 and also with a corresponding type wheel 33 on the lower rod 31, and operates both of these type wheels simultaneously. The gears 34 are loosely mounted on a sleeve 35 which is supported by a rod 36 projecting from a printer frame 37 (Fig. 1).

Secured to each of the gears 34 is a ratchet 38 normally held against movement by a spring-pressed retaining pawl 39. Also operating with the ratchets 38 is a multi-tined pawl 40 fast on a rod 41 carried by a yoke 42 pivotally supported by the rod 36. The means for transferring from lower to higher orders is of the deep notch variety.

which is so old and well known that no description thereof will be given herein.

Integral with the yoke 42 is a segment 43 meshing with the teeth of a segmental gear 44 fastened to a shaft 45 projecting from the frame 37. Also fast on this shaft is an arm 46 pivoted to a link 47, which at its lower end has a notch 48 cooperating with a pin 49 carried by a lever 50 secured to a shaft 51. Shaft 51 is given first a counter-clockwise and then a clockwise rotation on every operation of the machine as described in the above mentioned patent and with the parts in the positions shown in Fig. 1, it is clear that the link 47 will be moved downwardly when the shaft 51 is rocked counter-clockwise. This movement of link 47 rocks the arm 46, shaft 45 and segment gear 44 clockwise. The yoke 42 will, therefore, be rocked counter-clockwise a sufficient distance for the driving pawl 40 to move the units ratchet wheel 38 one step. As the lever 50 returns to its normal position, the link 47 will be raised and the driving pawl will be returned to the position shown in Fig. 1.

Disabling consecutive number actuator by total lever

Since it may be undesirable to print a consecutive number when a total is being taken, mechanism is provided for automatically disabling the consecutive number actuator whenever the total lever is moved out of its adding position preparatory to printing totals. This mechanism is shown and described in the above mentioned patent, and for this reason, the description thereof in this application will be brief. As is well known, machines of this type are provided with a total lever 60 (Fig. 3) having a plate 61, pivotally mounted on a stud 62. Pivoted to this plate is a link 63, which at its lower end, is pivoted to an arm 64 secured to a spiral segment 66. Meshing with the segment 66 is a spiral pinion 67 fastened to a shaft 68 supported by the frame 37. Also secured to the shaft 68 is a segment 69 (Figs. 1 and 3), which cooperates with a roller 70 carried on the right hand end of a pitman 71. The pitman 71 is pivotally connected near its right hand end to a bell crank lever 72 and at its left hand end, is bifurcated and cooperates with a pin 73 projecting from the frame 37. The pitman 71 also has a slot 74 formed therein through which projects a pin 75 carried by the link 47. With the parts in the positions shown in Fig. 1, the link 47 may be moved first downwardly and then upwardly without any interference from the pitman 71.

However, if the total lever 60 is moved in either direction out of its normal adding position, (shown in Fig. 3) the link 63 will rock the arm 64 and spiral segment 66 either clockwise or counter-clockwise, and this

movement, through the spiral gear 67 and shaft 68, will rock the segment 69 either counter-clockwise or clockwise, depending upon the direction in which the total lever is moved. When the segment 69 is given this movement, the pitman 71 will be forced toward the left, due to the engagement of the roller 70 with the periphery of the segment, and as the pin 75 on the link 47 projects through the slot 74 in the pitman 71, the movement of the pitman toward the left will carry the link with it. The link 47 has a notch 78 formed therein which will then cooperate with the stationary pin 73. The notch 48, which is normally in engagement with the pin 49 of the driving lever 50, will be disengaged from said pin, and therefore, when the lever 50 is given its counter-clockwise and clockwise movements, the link 47 will not be moved and the consecutive number type wheels will not be turned.

Key-operated means for disabling consecutive number wheels

Means is also provided for disabling the consecutive number wheels by a manually operated key. The bell crank lever 72 is fastened to a short shaft 80 mounted in the frame 37, and has an inclined arm 81 which is adapted to cooperate with a pin 82 carried by a plunger 83 (Figs. 1 and 5). This plunger has two ears 84 and 85 formed thereon. A key 86 has integral therewith a shank 87 which passes through an opening in the ear 85. Said shank terminates at its lower end in a reduced portion which passes through an opening in the ear 84. The upper face of the ear fits snugly against the shoulder formed at the juncture of the reduced end of the shank, and suitable fastening means, as a washer mounted on the reduced end below the ear 84, connects the shank and plunger to permit the shank to be rotated relatively to the plunger, and enforce simultaneous longitudinal movement of the plunger and shank. When the key 86 is pressed downwardly, the plunger 83, which is bifurcated at its lower end to embrace the shaft 80, will be carried downwardly therewith, thus causing the pin 82 carried thereby to engage with the inclined arm 81 of the bell crank lever 72 and rock this lever clockwise. As this bell crank lever is pivoted to the pitman 71, the pitman will be moved toward the left and the consecutive number wheel-actuating mechanism will be rendered inoperative in the same manner as above described in connection with the movement of the total lever 60. The key 86 is held in its normal, undepressed position by a spring 88 stretched between a pin carried on the bell crank lever 72 and a pin 89 on an arm 95 later referred to.

When the key is depressed, it will be latched in its depressed position by the fol-

lowing mechanism: A latching pawl 90 is pivoted on a stud 91 and has a downwardly extending tail 92. The pawl 90 constantly tends to rock in a clockwise direction due to the action of a spring 93 extending from the pin 89 to a pin on the pawl. Therefore, when the key 86 is depressed, the tail 92 of the pawl under influence of its spring 93, will be moved above and into the upward path of a shoulder 94 formed on the plunger 88, which will hold the key in its depressed position.

Means is provided to release the key near the end of each operation when it is depressed in the above described manner. This means consists of the arm 95 fastened to a shaft 96, which receives a short counter-clockwise and then a clockwise movement at each operation of the machine by means shown in the before mentioned patent. This movement will rock the upper end of the arm 95 into contact with an inclined surface 97 of the pawl 90, which will rock the pawl counter-clockwise, thereby disengaging the tail 92 from the shoulder 94 and permitting the spring 88 to return the key to its normal undepressed position.

Mechanism is provided for releasing the key 86 before the operation of the machine takes place, when the key has been depressed by mistake. The shank 87 of the key carries a pin 98 which, when the key is depressed, will move downwardly into the plane of a plate 99 riveted to the side of the pawl 90 (Fig. 1). It can, therefore, be seen that if it is desired to unlatch the key 86, all that it is necessary to do is to rotate the key in a counter-clockwise direction, as viewed from the top, which will bring the pin 98 into contact with the plate 99 and move the tail 92 of the pawl away from the shoulder 94 of the plunger 88, thereby releasing the key and permitting it to move upwardly to its normal position.

When it is desired to have the consecutive number mechanism disabled during a plurality of operations, the key 86 is depressed and then rotated in a clockwise direction, as viewed from the top, a knurled surface being provided on the key to facilitate this operation. The shank 87 of the key carries a pin 100, which, when the key is depressed and rotated clockwise, moves beneath a keeper 101 (Fig. 5) depending from a plate 102 secured to the frame 37. This keeper 101 is recessed to accommodate the pin 100, and when the operator removes his finger from the key 86, the pin 100 seats itself in the recess of the keeper 101. A forked spring 103 secured to the plunger 88 cooperates with the opposite ends of a pin 104 passing through the lower end of the key shank 87.

When the key 86 is depressed, the shoulder 94 is lowered farther than necessary to permit the latch 90 to engage the shoulder, so that when the key is rotated to move the pin

100 beneath the recess of the keeper 101, and the operator removes his finger from the key 86, the spring 88 returns the key upwardly until the pin 100 is seated in the recess, and the tail of the latching pawl engages the shoulder 94, so as to disable the consecutive numbering mechanism for a plurality of operations. During each operation of the machine, the pawl is disengaged from the shoulder 94, but this is an idle operation since the plunger 88 and key 86 are held depressed by the pin 100 in the recess of the keeper 101, and are retained in such positions throughout one or more operations until the key is manually released.

When the key 86 is depressed and rotated clockwise as above described, the action thereof causes the left end of the pin 104 (Fig. 1) to flex the left fork of the spring 103. When it is desired to release the key 86 from the keeper 101, a slight depression of the key to disengage the pin 100 from its keeper 101, will permit the spring 103 to rotate the key 86 counter-clockwise.

Such slight depression of the key 86 releases the key from the keeper 101, but the key cannot rise to its normal position since the pawl 90 holds the plunger 88 against completely releasing. Therefore, in order to completely release the key 86 so that it may be raised to its normal position, it is necessary to turn it counter-clockwise so that its pin 98 will strike the plate 99 and disengage the pawl from the plunger 88. When this is done, the spring 88 then restores the key 86 and plunger 88 to their undepressed positions. The right fork (Fig. 1) of the spring 103 will then rotate the key clockwise, if the operator has not already done so.

The chief function of the forked spring 103, however, is to prevent the pin 100 from accidentally getting beneath the keeper 101 when it is not desired to disable the consecutive number mechanism.

Modified form of consecutive number disabling mechanism.

In Fig. 4 there is shown a modified form of mechanism for disabling the consecutive number mechanism during either a single operation or throughout a plurality of operations. This mechanism will now be described. Secured to the shaft 80 is a bell crank lever 72 identical with the bell crank lever 72 shown in Fig. 1. A key 111 has fastened thereto a downwardly extending shank 112, which, at its lower end, is bifurcated to embrace the shaft 80. This shank 112 carries a pin 113 which is adapted to cooperate with an inclined arm 114 of the bell crank 72. When the key 111 is depressed, the pin 113 will rock the bell crank lever 72 clockwise, and as this lever is pivoted to the pitman 71, as shown in Fig. 1, the pitman and the mechanism actuated thereby will be operated to

disable the consecutive number actuating mechanism, as above described. The key is held in its normal undepressed position by a spring 115 stretched between a pin on the bell crank lever 72 and a suitably located pin 116 on the machine frame.

The means for latching the key 111 in depressed position for a single operation only will now be described. The shank 112 has a shoulder 117 which normally lies just above a flattened pin 118 carried by a bell crank lever 119 pivoted on the machine frame. The pin 118 is normally held in contact with the lower inclined edge 121 of the shoulder 117 by a spring 120 extending between one arm of the bell crank 119 and the pin 116. When the key 111 is depressed, the inclined edge 121 of the shoulder 117 will force the pin 118 outwardly until the shoulder 117 passes below the pin, whereupon the spring 120 will rock the bell crank 119 clockwise and move the pin into position above the shoulder 117, thereby holding the key 111 depressed. As described in connection with the first form of the invention shown herein, there is a shaft 96 which receives a counter-clockwise and then a clockwise movement near the end of every operation of the machine. Fastened to this shaft is an arm 122 which carries a pin 123 cooperating with an inclined surface 124 of the bell crank 119. It is apparent from Fig. 4 that when the shaft 96 is given its counter-clockwise movement near the end of the operation, the pin 123 will cause the bell crank 119 to rock counter-clockwise, due to the engagement of this pin with the inclined surface 124, a sufficient distance to remove the pin 118 from above the shoulder 117 of the shank 112. The key 111 is then free to return to its normal undepressed position under the influence of the spring 115.

The following described means are provided for latching the key in its depressed position during a plurality of operations, or until manually released. The shank 112 has an opening 125 formed therein through which projects a stud 126 carried by the machine frame. This stud has a flattened side 127 on its under side. A shoulder 128 is formed in the wall of the opening 125 in such a position that if the key 111 is depressed and then moved sidewise with the shaft 80 as a pivot, the shoulder will move beneath the flattened side 127 of the stud 126 and hold the key in its depressed position. It is evident that this position will be retained by the key until it is moved manually far enough to disengage the shoulder from the flattened side 127, whereupon the spring 115 will raise the key to its normal, undepressed position, upon a subsequent operation of the machine during which the arm 122, through stud 123, rocks the bell crank 119, to release the key.

While the form of mechanism herein shown and described is admirably adapted to fulfill the objects primarily stated, it is to be un-

derstood that it is not intended to confine the invention to the one form or embodiment herein disclosed, for it is susceptible of embodiment in various forms all coming within the scope of the claims which follow.

70

What is claimed is:

1. In a machine of the class described having a consecutive counter and actuating means therefor, the combination of a depressible and rotatable key for disabling said actuating means, a latch for holding said key depressed, means operable during the operation of the machine to trip said latch to release said key, and a tripping means carried by said key and adapted when said key is rotated previous to an operation of the machine, to trip said latch and release said key.

75

2. In a machine of the class described having a consecutive number mechanism and means to actuate the same; the combination of means to disable the actuating means, including a key having a normal position and at least one adjusted position; means to latch the key in its adjusted position; and means operable by the key when manipulated 80 in its adjusted position, to trip the latch and release the key.

85

3. In a machine of the class described having a consecutive number mechanism and means to actuate the same; the combination of means to disable the actuating means, including a depressible and rotatable key; means to latch the key when depressed; means operable by the key when rotated to trip the latch to release the key for return to 90 normal position; and yielding means to prevent accidental shifting of the key to trip the latch.

95

4. In a machine of the class described having a consecutive number mechanism and means to actuate the same; the combination of means to disable the actuating means, including a depressible key adapted for longitudinal movement toward and from its normal position, and for rotary movement in either direction in its depressed position; and yielding means to prevent accidental rotary movement in either direction.

100

5. In a machine of the class described having a consecutive number mechanism and means to actuate the same; the combination of means to disable the actuating means, including a depressible key adapted for longitudinal movement toward and from its normal position, and for rotary movement in its depressed position; means to latch the key when shifted longitudinally to its effective position; and means operated by the key, when rotated to trip the latch.

115

6. In a machine of the class described, the combination with an operable mechanism, and means to actuate the mechanism; of a key having two adjusted positions in addition to its normal idle position, and yieldable means movable bodily with the key and tending to 120

120

125

130

prevent accidental adjustment of the key from its first adjusted position into its second adjusted position.

7. In a machine of the class described having a consecutive number mechanism and means to actuate the same; the combination of a depressible and rotatable key to control the effectiveness of the actuating means; projections on the key; and yielding means, including a plurality of spring members to cooperate with the projections on the key to prevent accidental rotary movement of the key in either direction.

8. In a machine of the class described having a consecutive number mechanism and means to actuate the same; the combination of a depressible and rotatable key to control the effectiveness of the actuating means; a projection on the key; and a spring in contact with the projection to prevent accidental rotary movement of the key and to aid in restoring the key to a previously assumed position.

9. In a machine of the class described, the combination of an operable mechanism; and means to actuate the mechanism; of a slideable and rotatable manipulative device having attached thereto a slideable and non-rotatable plunger, the manipulative device adapted when slid, to operate the plunger to disable the actuating means; and yieldable means supported on the plunger and tending to prevent accidental rotation of the manipulative device after the same has been slid.

25 10. In a machine of the class described, having a consecutive number mechanism and means to actuate the same, the combination of a key having two adjusted positions in addition to its normal idle position, means to disable the actuating means when the key is moved to the first of its adjusted positions, means to retain the key in its second adjusted position after being so moved from the first adjusted position, and means energized by the key when moved to its second adjusted position to assist in releasing the key from such position.

11. In a machine of the class described, a disabling mechanism including a depressible and rotatable key, a latch for holding the key depressed, when so moved, an additional latch for holding the key depressed irrespective of the first latch, the first latch being so situated with respect to the second, that release of the key from the second latch leaves the key still under control of the first latch.

55 12. In a machine of the class described, a disabling mechanism including a depressible and rotatable key, a latch for holding the key depressed, when so moved, an additional latch for holding the key depressed irrespective of the first latch, the first latch being so situated with respect to the second, that movement of the key to release the same from the second latch will leave the key still under the

control of the first latch, and means connected to the key and cooperating with the first latch, to release the key from said first latch upon further movement of the key in the same direction.

In testimony whereof I affix my signature.
BERNIS M. SHIPLEY.
